ATOMIZER

Karl Flury, Adliswil, Zurich, Switzerland, assignor to
Defensor A. G., Zurich, Switzerland

Application June 6, 1955, Serial No. 513,530

Claims priority, application Switzerland April 15, 1955

12 Claims. (Cl. 183—18)

The present invention relates to an atomizer having arranged within a casing a motor-driven rotary member for producing an air current and for throwing out a fluid against baffles which surround the rotary member at a distance and lie in the range of the air current.

Such atomizers are known and serve for instance for air humidifying in rooms. The disadvantage of these atomizers resides in the comparatively great noise which is constantly heard during operation and is partially caused by breaking up fluid on the baffles, whereby parts of the apparatus start to oscillate which, assisted by the casing as a resonator, are liable to amplify the partly unavoidable noises still more.

The present invention aims at a substantial attenuation of the audible noises to such extent that the atomizer may be operated even in quiet rooms, say, living rooms and offices, without causing disturbance by its noise.

With the atomizer according to the invention this object is essentially achieved in that means consisting of sound-absorbing material are provided within the casing in order to attenuate the noises arising in the operation of the atomizer, and that at least one part of these means is designed and arranged in such manner as to be able at the same time to eliminate larger liquid drops from the fluid mist, by deflecting the mist.

Further features of the invention will appear from the claims, description and accompanying drawing which latter represents by pure way of example two preferred forms of embodiment incorporating the invention.

In said annexed drawing:

Fig. 1 shows partly in lateral view and partly in vertical section the first form of embodiment of the atomizer;

Fig. 2 shows in similar representation part of the second form of embodiment.

The atomizer shown in Fig. 1 comprises an outer casing 11, 12 consisting of a tank-shaped bottom part 11 and a top part 12 provided with a central aperture 13. The bottom part 11 of said casing serves as receptacle for a fluid 14 to be atomized, say, water. The top part 12 of the casing is mounted on a frame ring 15 having attached thereto a few tubular legs 16 each of which is supported on the bottom of the lower part 11 by means of a foot 17 of sound-deadening material, say, rubber-like plastics. Provided between the upper rim of the bottom part 11 and the top part 12 or annular frame 15 is an air admission gap which extends round the casing 11, 12. The inlet path 19 for the air current is arranged between the circumferential wall of the bottom part 11 and a circumferential wall of the annular frame 15, serving as partition. This inlet path, of annular cross-section, extends round the circumference of the casing and includes an air filter 21 to retain larger dust particles of the entering air. The filter 21 is formed by a round brush extending along the periphery of the casing and resting with its bristles of, say, polyethylene, both against

2

the circumferential wall of the casing bottom part 11 as well as against the partition 20 of the annular frame 15. Said brush 21 is supported by several holding lugs 22 provided on a supporting ring 23 connected to the annular frame 15, on which the bristles of the brush 12 can rest in the space between the individual lugs 22.

The interior of casing 11, 12 includes an internal housing which comprises two parts 31 and 32, the bottom part 31 being attached to the annular frame 15 by several bolts 33. The internal housing 31, 32 contains an electric driving motor 34 with vertical shaft 35. The motor 34 has two casing parts 36 and 37 fitted with matched flanges 38 and 39 interconnected by means of (not visible) hollow rivets. Riveted to the bottom of part 31 of the internal housing 31, 32 are several bolts 40 each having an upwardly projecting extension 41 of smaller diameter. These extensions 41 protrude with clearance through said hollow rivets on said flanges 38 and 39. Rings 42 consisting of some resilient rubber-like material, preferably synthetic material, are pushed onto each extension 41 and clamped between the thicker bolt bottom 40 and the flange 39 or between the flange 38 and a disk 43 which is secured to the extension 41, for instance by means of a spring clamping disk 44. In this way the motor 34 is resiliently mounted with respect to the housing bottom part 31. Downwardly the internal housing 31, 32 is sealed airtight by a gasket 45 of soft elastic material interposed between the motor casing part 37 and the bottom part 31 of the internal housing 31, 32.

The upper end of the motor shaft 35 carries a blower wheel 50 for cooling the motor 34, while a hub 51 consisting of some resilient, sound-absorbing material is firmly mounted on the lower end of the shaft 35 projecting out of the internal casing 35. Fixed to said hub by means of hollow rivets 52 is a rotary member 53—57 serving to produce an air current through the casing 11, 12 and to throw out fluid. Said rotary member includes a disk-shaped, slightly conical part 53 which, together with a suction cone 54, open below and dipping into the fluid 14, consists of a single piece of sheet-metal. Furthermore, said rotary member includes a second disk-shaped part 55 provided with fan vanes 56. The two parts 53 and 55 are superimposed and lie flat on each other with tension under the influence of their own elasticity in order to attenuate the oscillation of the rotary member by friction of the parts 53 and 55 against each other. Toward the centre of the disk 55 a collar 57 is formed which, tightly surrounding the suction cone 54 outside, is located above the level of fluid 14 and is intended for throwing off by centrifugal force any fluid rising outside the cone 54. The hub 51 is provided with several outstanding extensions 58 which may be removed as required for the purpose of balancing the whole rotor.

Located in the centre of the casing bottom part 11 is a cup 60 having a circular wall surrounding the suction cone 54 at a distance and projecting beyond the level of the spray collar 57 to catch the fluid thrown from collar 57, in order to avoid its impinging with considerable noise against the circumferential wall of the casing bottom part 11. The annular wall of the beaker 60 has several openings 61 for the fluid 14. These openings 61 are arranged above the tank bottom and below the level of fluid 14 in such a way that any impurities, such as dust, fibres, etc., lying either on the bottom of the lower part 11 and/or floating on the fluid 14 cannot reach the interior of the cup 60 and then be thrown out. Further, several radially extending ribs 62 are firmly arranged on the bottom of the cup 60 to counteract any rotary motion of the fluid there.

The rotary member 53—57 is surrounded at a distance

by an atomizer rim 65 i. e. a disintegrator ring which, by means of some resilient members 66 of sound-absorbing material, is supported on the annular frame 15, as shown at the right in Fig. 1. The atomizer rim 65 has a great number of outwardly pressed lugs 67 and passage openings 68 therebetween. The rim 65 may consist of sheet-metal and be preferably provided with a covering of sound-absorbing material, such as polyethylene; but it may also be made of sound-absorbing synthetic material. The lateral faces of the lugs 67, or the outer faces of the covering provided thereon, form baffles adapted to atomize the fluid thrown off the circumferential rim of the rotary member 53-57. The already mentioned partition 20 of the annular frame 15 likewise encloses the rotary member 53-57 and is located at some distance outside the atomizer rim 65. The inner side of the partition 20 is covered with a sleeve 69 consisting of some sound-absorbing material, being upwardly extended and covers with its upper part 70 the joint between the casing top part 12 and the annular frame 15, rendering them tight. The inner surface of the bottom part 69 of said sleeve forms a further baffle for intercepting larger fluid drops which pass through the openings 68 of the atomizer rim 65 and are not carried along by the rising air current.

Formed at the annular frame 15, adjacent to partition 20, is an annular collector trough 71 into which the fluid thrown toward the sleeve 69 and the accumulated condensate may flow off noiselessly. From the trough 71 the fluid can return to the casing bottom part 11 through the tubular legs 16 and the hollow feet 17. To that effect the feet 17 are provided with lateral passage openings 72.

Provided between the circumferential wall of the casing top part 12 and the circumferential wall of the internal housing 31, 32 there is an outlet path 75 of annular cross-section for the air current produced by means of the rotary member 53-57 and the fluid mist caused by atomizing. In this outlet path 75 there is a baffle 76 consisting of a sound-absorbing material, say, polyethylene or the like, preferably in the form of an annular disk seated firmly under the influence of its own elasticity in a peripheral groove 77 of the internal housing part 31. Said annular disk 76 is stiffened by ribs 78 formed thereon; it prevents direct escape of the noise from the air outlet path 75, unavoidable in fluid atomizing, and deflects the fluid mist carried along with the air current in such manner as to eliminate larger fluid drops therefrom. Located within the deflection range of the baffle 76 is the top part 70 of the sleeve 69 consisting of sound-absorbing material, on the wall opposite the baffle 76, whereby noises possibly caused by air turbulence will be damped. For the same purpose several guide vanes 79 are rigidly mounted in the outlet path 75 to counteract the rotation of the air flowing out. These guide vanes 79 are fastened to the hood-shaped top part 32 of the internal housing. The hood 32 closes the internal housing 31, 32 upwards and consists, together with the guide vanes 79, of some sound-absorbing material.

The atomizer has a strap 81 designed as a handle of resilient sound-absorbing material. Provided at the ends of said strap 81 are two trunnions 82 engaging corresponding recesses in the circumferential wall of the bottom part 31 of the internal housing. Furthermore, said strap 81 has at each end portion two cams 83 and 84 which engage over a shoulder at the periphery of the hood 32 or at the upper rim of the top part 12 of the outer casing 11, 12 and secures in position the hood 32 and casing part 12 under the influence of the elasticity of the strap. Interposed between the inner housing part 31 and the hood 32 is moreover a resilient gasket 85.

The already mentioned bolts 33 are hollow and are connected also by means of hollow screws 90 to the partition 20 of the annular frame 15 and to the sleeve 69. In each of the recesses of the screws 90 of, say, two diametrically opposite bolts 33, there is a pin 91 slidably guided lengthwise and carrying at its outward end a push-

button 92 with a latch member 93. The reduced portion of the pin 91 has arranged around it a coil spring 94 located within the hollow space of the related screw 90 and rests with one end against a shoulder 95 of screw 90 and with the other end against a shoulder of pin 91. Said spring 94 tends to hold the latch member 93 in engagement with the curled rim 96 of the casing bottom part 11 and to push the button 92 inwards into the air admission gap 18. Thus the bottom part 11 of the outer casing is removably secured to the annular frame 15 and hence to the casing top part 12. By pushing the buttons 92 inwards against the action of the springs 94, the latch members 93 can be brought out of engagement with the rim 96, whereupon the casing top part 11 serving as fluid receptacle may be separated from the rest of the atomizer. To prevent said pins 91 from passing completely out of the screws 90, each pin has at its end a stop member 97.

Through the hollow space of a screw 90 provided with a pin 91 the electric connecting cable, not shown, for the motor may be introduced.

The action of the aforescribed atomizer is known per se. The rotary member 53-57 produces an air current in the direction of the arrows indicated in Fig. 1. Further, by means of the rotating suction cone, fluid 14 is delivered upwards and thrown out by the disk-shaped part 53 of the rotary member 53-57. The fluid film thus produced and traveling beyond the peripheral rim of the part 53 is broken up partly by centrifugal action and partly by the air current and converted into mist droplets and larger fluid drops, which are thrown against said baffles and thus become further broken up. The produced fluid mist is carried off by the air current, whereby due to the deflection at the baffle plate 76 any larger drops carried along will be eliminated.

In addition to the constructional simplicity, the atomizer as described hereinbefore has the advantage of being practically noiseless in operation. The round brush, serving at the same time as a filter, attenuates by its contact with the circumferential wall of the casing part 11 and partition 20 any oscillation setting up in these parts and prevents the exit of noises from the interior of the atomizer through the air inlet path 19. Inasmuch as the impact surfaces are provided on sound-absorbing material, the noises per se caused by the impact of the fluid are already considerably reduced. The resilient supporting members 66 for the atomizer rim 65 keep any oscillation of the latter away from the other parts of the apparatus. The sleeve 69 of sound-absorbing material absorbs on the one hand the impact noises of the larger fluid drops and on the other hand any oscillation arising in the partition 20. The baffle 76 not only prevents direct exit of unavoidable atomizer noises through the path 75, but at the same time damps any oscillation setting up in the inner housing part 31. The upper part 70 of the sleeve 69 not only improves the sealing between the annular frame 15 and the casing part 12, but also damps oscillation of these parts and the noises otherwise arising on deflection of the air current. The hood 32 of the inner housing 31, 32, consisting of sound-absorbing material, keeps back the noises caused by motor 34 and blower wheel 50 within the casing. Any vibrations of the motor 34 will be kept away from the inner housing 31, 32 by the resilient sound-absorbing disks 42 and gasket 45. The elastic and sound absorbing hub 51 prevents the motor vibrations from being transferred onto the rotary member 53-57 which itself is damped against oscillation by the resilient contacting of its parts 53 and 55.

It may prove advantageous to have one disk-shaped part 55 and the fan vane 56 connected thereto provided with a layer of sound-absorbing material, or itself made of some sound-absorbing material.

The elastic strap 81 secures in a simple manner the relative position of the parts 12, 31 and 32 so as to prevent any chatter thereof. Similarly, the feet 17 prevent any chatter of the legs 16 on the bottom of the casing

lower part 11. Also the latch members 93 prevent chatter noises or the like, as they hold firmly the lower part 11 with respect to the rest of the atomizer.

The construction of the hub 51 of resilient material involves the further advantage that practically the rotary member 53-57, with lower part 11 of the outer casing 11, 12 removed, cannot be deformed by blows or knocks, because it is held resiliently.

The airtight sealing of the inner housing 31, 32 achieved by gasket 45 against the suction side, i. e. the low-pressure side of the rotary member 53-57, has for its purpose to prevent any air flowing out downwards from the inner housing because otherwise the moisture-laden air would continue to flow into the inner housing between bottom part 31 and hood 32, and the motor 34 would come to lie in a moist atmosphere.

It is known that, when atomizing fluids, a cooling effect will arise due to evaporation of a part of the fluid droplets. The air leaving the atomizer as saturated with moist mist is under circumstances appreciably cooler than the air drawn into the apparatus. Such cooling effect may often be desirable. In case it is undesirable, a heater 99 may be provided in the current path 75 of the air, as indicated in Fig. 1 by chain-dotted lines. This heater preferably consists of electrical resistance elements which are arranged insulated in tubes.

The second form of embodiment illustrated in Fig. 2 shows basically the same structure as in Fig. 1. Like reference numerals indicate like parts in the two forms of embodiment. It is presumed that the atomizer represented in Fig. 2 incorporates a heater (not shown) similar to the device 99 of the first form. The difference of the second form consist in the following:

In this case the motor 34 has a hollow shaft 35a through which passes a rod 101, preferably of non-magnetic material. The lower extremity of said rod carries a valve 102 of resilient material, which may be brought into contact with the inner surface of the suction cone 54 with a view to stop the delivery of fluid to the disk-shaped part 53 of the rotary member 53-57. By lifting the rod 101 the valve 102 can be brought into the open position as shown by broken lines. In this open position the upper face of the valve 102 can make contact with the lower extremity of the hollow shaft 35a in order to seal the inner space thereof against ingress of fluid. Within the range of the upper face of the valve 102, this is provided with a spraying collar 103 serving to throw out any fluid present.

At the top end of the hollow shaft 35a, an armature 105 of an electro-magnet 106 is connected to said rod 101. The coil 107 of the electro-magnet is mounted firmly above the motor 34 by means of a holding member 108 and some spacer bolts 109, of which only one is shown. The armature 105 is freely movable with respect to the coil 107 and can turn along with the rod 101 upon rotation of the hollow shaft 35a. By energizing the magnet 106, the valve 102 can be brought into its open position, while with magnet de-energized, it takes up the closing position by gravity.

Fixed to the hood 32 of the inner housing 31, 32 is a multi-step electric switch 111 which can be actuated by means of a rotary knob 112. The switch is in connection with the coil 107 of the electro-magnet 106 and with the heater 99. The heater is preferably of such design that selectively only part of the same or the whole heater may be switched-on according to the position of the switch 111.

In one position of the switch 111 the motor 34 is switched off, while it is in operation in all other positions, provided the apparatus is joined to a suitable source of energy. In a second position of the switch 111 the motor 34 is "on" and the magnet 106 is energized, so that the valve 102 will take up its open position. The apparatus then works exactly similarly to that described with reference to Fig. 1, in that only air is delivered and fluid is atomized. In a third position of the switch 111 still a

part of the electric heater 99 is additionally switched-on in such a way that cooling of the air current taking place when the liquid atomizes, will be substantially nullified by suitable heating. In a fourth position of the switch 111 the whole heater is switched-on so that the air current saturated with fluid mist and flowing out of the apparatus may be warmed additionally for the purpose of heating rooms. In a fifth position of the switch 111 the magnet 106 remains de-energized, while the motor 34 operates, and part of the heater 99 is switched-on for the purpose of producing a warm air current. In a sixth position of the switch the whole heater 99 may be in operation, while the magnet 106 remains unexcited. Finally a further position of the switch is conceivable, in which the motor operates for producing an air current which is neither heated nor humidified.

As compared with the form of embodiment in Fig. 1, the apparatus shown in Fig. 2 requires a comparatively small additional expenditure, but presents the advantage of having a greater variety of applications.

What I claim is:

1. An atomizer for atomizing liquids and discharging the same in the form of an aerosol mist, comprising an outer casing having a discharge opening and an air inlet opening, an internal housing within and spaced from said casing to provide an exit path between said casing and said internal housing, a motor incorporated within said internal housing, a receptacle for liquid in the lower part of said casing, said motor including rotary means for moving air through said casing from said inlet opening to said discharge opening and rotary atomizer means extending into the liquid for introducing liquid particles to said moving air to form a mist therein, at least one annular baffle of elastic and sound-absorbing material provided in said exit path and seated by its own elasticity in a circumferential recess provided in the external periphery of said internal housing, said baffle serving to force the mist in a curved path and thus prevent direct exit of heavier particles in the mist and also prevent transfer of high pitch atomizer noise through said discharge opening, and means for noiselessly conducting condensate and other liquid droplets back to said liquid receptacle.

2. An atomizer as defined in claim 1 wherein a gap between said internal housing and a housing of said motor toward said rotary means is sealed air-tight by sound-absorbing material.

3. An atomizer for atomizing liquids and discharging the same in the form of an aerosol mist comprising, an outer circular casing having a discharge opening and an air inlet opening, said outer casing including a bottom part and a top part, said inlet opening being defined by a gap between said bottom and top parts and extending circumferentially around said casing, a circular partition wall secured by an air-tight seal at the lower edge of said top part and being arranged within and spaced from said bottom part to provide an air inlet path between said bottom part and said partition wall, an annular brush arranged in said inlet path and resting with its bristles both against a circumferential wall of said bottom part as well as against said partition wall, said brush serving to filter the air and to damp vibrations of the adjacent walls, an internal housing within and spaced from said outer casing to provide an exit path between said outer casing and internal housing, means for moving air through said outer casing from said inlet opening to said discharge opening, a receptacle for liquid in the lower part of said outer casing, atomizer means for introducing liquid particles to said moving air to form a mist therein, at least one baffle of sound-absorbing material, said baffle being located in said exit path to force the mist in a curved path and thus prevent direct exit of heavier particles in the mist and exit also of high pitch atomizer noise through said discharge opening,

and means for noiselessly conducting condensate and other liquid droplets back to said receptacle.

4. An atomizer as defined in claim 3 wherein said atomizer means comprises a disintegrator ring arranged within and spaced from said partition wall, the inner surface of said partition wall being provided with a covering of sound-absorbing material to form a sound-dead impinging surface for the liquid particles thrown out through said disintegrator ring.

5. An atomizer as defined in claim 3 wherein said partition wall joins with its lower edge to a collector trough for the condensate and liquid droplets, said means for noiselessly conducting said condensate and droplets to said receptacle being tubular legs supporting said trough, the lower end of said legs being provided with feet of sound-absorbing material and standing on the bottom of said receptacle.

6. An atomizer for atomizing liquids and discharging the same in the form of an aerosol mist comprising, an outer casing, said casing having a discharge opening and an air inlet opening, an internal housing within and spaced from said outer casing to provide an exit path between said outer casing and said internal housing, means for moving air through said outer casing from said inlet opening to said discharge opening, a receptacle for liquid in the lower part of said outer casing, atomizer means for introducing liquid particles to said moving air to form a mist therein, said atomizer means including a pair of disk-shaped superimposed parts which by their own elasticity lie flat against each other so as to damp vibration by friction of said parts on each other, at least one baffle of sound-absorbing material, said baffle being provided in said exit path to force the mist in a curved path and thus prevent direct exit of heavier particles in the mist and also exit of high pitch atomizer noise through said discharge opening, and means for noiselessly conducting condensate and other liquid droplets back into said receptacle.

7. An atomizer as defined in claim 6 wherein one of said disk-shaped parts is provided with several fan vanes and consists together with these of sound-absorbing material.

8. An atomizer for atomizing liquids and discharging the same in the form of an aerosol mist comprising an outer casing having a discharge opening and an air inlet opening, an internal housing within and spaced from said casing to provide an exit path between said casing and said internal housing, a motor incorporated within said internal housing, a receptacle for liquid in the lower part of said outer casing, said motor including a rotary vaned disk member in the lower part of said housing for moving air through said casing from said inlet opening to said discharge opening, said rotary member also including a suction cone open at its lower end and dipping into the liquid in said receptacle, said suction cone and vaned disk member serving respectively to raise the liquid in said cone and introduce liquid particles to the

5 moving air to form a mist therein, a valve arranged movably within said cone to control liquid flow through said cone, said motor having a hollow shaft supporting said cone and disk member and through which passes a rod carrying said valve, means to operate said rod from the exterior of said casing thereby to operate said valve, at least one annular baffle of elastic and sound-absorbing material provided in said exit path and seated by its own elasticity in a circumferential recess provided in the 10 external periphery of said internal housing, said baffle serving to force the mist in a curved path and thus prevent direct exit of heavier particles in the mist and also prevent transfer of high pitch atomizer noise through said discharge opening, and means for noiselessly conducting 15 condensate and other liquid droplets back to said liquid receptacle.

9. An atomizer as defined in claim 8 wherein said rod at its upper end is provided with an armature of an electromagnet, said armature being freely movable and rotatable with respect to a stationary magnet coil and by whose excitation said valve can be moved with respect to said cone to open and close the same.

10. An atomizer as defined in claim 9 wherein said valve is movable to a position closing off the lower end 25 of said hollow shaft.

11. An atomizer as defined in claim 9 and which further includes an electric heater incorporated within said casing to enable heating of the moving air, and electric switching means for controlling energization of 30 said magnet coil and said motor and said electric heater.

12. An atomizer as defined in claim 8 wherein said suction cone is surrounded by a stationary annular wall having passage openings for the liquid spaced from the bottom of said receptacle so that any impurities lying on 35 the bottom of said receptacle or floating on the surface of the liquid will be prevented from entering said cone and interfering with operation of said valve.
